UNITED STATES PATENT OFFICE.

FRED N. ROOT, OF KALAMAZOO, MICHIGAN.

TRACK-SCRAPER ATTACHMENT FOR STREET-RAILWAY CARS.

SPECIFICATION forming part of Letters Patent No. 699,573, dated May 6, 1902.

Application filed December 21, 1901. Serial No. 86,795. (No model.)

To all whom it may concern:

Be it known that I, FRED N. ROOT, a citizen of the United States, residing at the city of Kalamazoo, in the county of Kalamazoo 5 and State of Michigan, have invented certain new and useful Improvements in Track-Scraper Attachments for Street-Railway Cars, of which the following is a specification.

This invention relates to an improved track-
scraper attachment for street-railway cars.

The object of the invention is to provide a spring-pressure device for the scrapers which will enable a strong pressure to be applied at any time desired without danger of clogging 15 the scraper or seriously obstructing the progress of the car.

A further object is to provide a means in connection with such a scraper that will efficiently and thoroughly clean the rail itself without 20 interfering with the operation of the remaining parts of the scraper or requiring a close adjustment of the parts.

Further objects will definitely appear in the detailed description to follow.

25 I accomplish the objects of my invention by the devices and means described in the following specification.

The invention is clearly defined and pointed out in the claims.

30 A structure embodying the features of my invention is clearly illustrated in the accompanying drawings, forming a part of this specification, in which—

Figure 1 is a detail sectional view of my 35 improved attachment, taken on a line corresponding to line 1 1 of Fig. 2. Fig. 2 is a detail plan view of the wheels and scraper in relation to the frame of the car. Fig. 3 is a detail transverse sectional view taken on line 40 corresponding to lines 3 3 of Figs. 1 and 2. Fig. 4 is an enlarged detail sectional view taken on line 4 4 of Fig. 1. Fig. 5 is a detail view showing the method of attaching the springs to the rock-shaft and the formation

45 of the upper portion of the springs. Fig. 6 is a detail view of a modification of the rail-cleaning device in connection with the scraper. Fig. 7 is a detail view of the bottom portion of the rail-cleaner I". Fig. 8 is a detail view of the adjustable shoe I' of the rail-
scraper.

In the drawings all of the sectional views

are taken looking in the direction of the little arrows at the end of the section-lines, and similar letters of reference refer to similar 55 parts throughout the several views.

Referring to the lettered parts of the drawings, A is a frame or bottom structure of a street-railway car shown in conventional form.

B is a rock-shaft supported on the adjustable bearings D, which are adapted to adjust on the brackets C, supported on the under side of the car, a series of bolt-holes being provided in the bracket C to receive the attaching-bolt, as clearly appears in Fig. 1. Toward each end of this rock-shaft a spring E is attached, which extends upwardly and rearwardly and which is slightly twisted or bowed toward the center of the car and extends downwardly, and at the lower ends are carried scraper-blades E', which extend diagonally outwardly and rearwardly, their path being in front of the wheels F' of the street-car. The rock-shaft B is adjustable 65 by means of a bell-crank c at the front of the car, which is controlled by an adjustable handle a. The bell-crank is connected by a connecting-rod e to a downwardly-projecting arm B' on the rock-shaft B. It will thus be seen 70 that by adjusting the handle a up and down the position of the scrapers E' can be controlled and the pressure of the spring thereon regulated.

Secured to the rock-shaft B, preferably in 75 the same manner as the spring E, is an auxiliary or rail scraper I. This is a spring substantially the same as the spring E in general outline and is adapted to work independent of it. An adjustable shoe I' is on the lower 80 end of the spring I, the lower end of which projects normally lower than the scraper-blade E', the same being conformed to fit the top of the rail, as clearly appears in Fig. 8.

In the modified structure shown in Figs. 6 95 and 7 the auxiliary or rail scraper I" is secured to the spring E. It will be seen with this device that when there is a fall of snow by lowering the scrapers E' they will pass with a yielding pressure along the surface of 100 the ground, piling the snow out and away along each side. Then following immediately after is the auxiliary scraper I, which completely bares the rails, enabling the electric

contact, and consequently insuring the proper propulsion of the car. When there is only a very light snow on the rail, it will not be necessary to lower the scrapers E' clear down, 5 but the device can be lowered sufficiently so that the auxiliary scraper I just brushes the top of the rail. It will thus be seen that the device is effective for both light and heavy snow and that the sweeping of the rails by 10 brooms or the cleaning of the track with shovels and the consequent difficulties will be largely overcome by this device. Owing to the arrangement of the spring if a load of accumulated snow or slush becomes too heavy 15 for the spring to readily displace the scraper will be deflected inward until its resistance is such as to overcome the load, when it will throw the same to one side away from the track, so that there will be no danger of an 20 accumulation in front of the wheels and a clogging of the car on that account.

Having thus described my invention, what I claim as new, and desire to secure by Letters Patent, is—

25 1. The combination of the rock-shaft B; connections for adjusting the same; springs E curved upwardly and rearwardly and downwardly secured to the said rock-shaft, the upper portions of said springs being deflected inward; diagonal scrapers E' secured to the rear and lower ends of said springs; and auxiliary 30 spring-scrapers I secured to said rock-shaft and adapted to rest upon the rails, for the purpose specified.

35 2. The combination of the rock-shaft B;

connections for adjusting the same; springs E curved upwardly and rearwardly and downwardly secured to the said rock-shaft, the upper portions of said springs being deflected 40 inward; diagonal scrapers E' secured to the rear and lower ends of said springs and auxiliary spring-scrapers I secured to said rock-shaft, for the purpose specified.

3. The combination of the rock-shaft B; 45 connections for adjusting the same; springs E curved upwardly and rearwardly and downwardly secured to the said rock-shaft, the upper portions of said springs being deflected inward; diagonal scrapers E' secured to the 50 rear and lower ends of said springs, for the purpose specified.

4. The combination of the rock-shaft B; connections for adjusting the same; springs E curved upwardly and rearwardly and downwardly 55 secured to the said rock-shaft; diagonal scrapers E' secured to the rear and lower ends of said springs, for the purpose specified.

5. A scraper for street-railways carried on a suitable yielding spring; an auxiliary 60 scraper independently supported to the rear of and extending below the bottom of the same and adapted to yield independent of the main scraper.

In witness whereof I have hereunto set my 65 hand and seal in the presence of two witnesses.
